ABSTRACT: The device disclosed is an automatic warning to alarm approaching vehicle operators in the event a bridge slab or section is knocked out of position. An elongated tubular unit, pivotally mounted at the end of each adjacent span, counter-weighted to swing it to an upright position. At the other end of each tubular unit there is a flare having a pull cord by which it can be ignited, engaged over a pin on the opposite bridge section, located so as to dispose the unit in a horizontal, inactive position. If the spans shift relative positions, the cords are pulled, causing flares in each unit to ignite, and releasing the units so that they can swing into upright position on their respective spans by the action of the counter-weights. This places the burning flares in a clearly visible position above the roadway to warn of the bridge condition.

U.S. PATENT 3,522,790
BRIDGE FAILURE WARNING DEVICE

SUMMARY OF THE INVENTION

The invention consists of a least one pivoted arm attached to a bridge span element or the like, capable of swivelling from an inactive or lowered to an active or upright position, and having a flare or similar warning or alarm device on it that is moved from a conspicuous to an inconspicuous position and is activated when the arm moves to active, upright position. The alarm device is preferably a flare, and the pull cord for the flare, which also acts to retain the element in its inactive position, extends across to the adjacent span of the bridge so as to constitute both the flare actuator and a means for holding the arm down. If the spans shift their relative positions, the pull cord is stretched and actuates the flare at the same time releasing the element to swing to activated position. The upright shifting preferably is done by a counterweight arrangement and should be long enough to extend above the hand rail of the bridge.

In the drawing:

FIGURE 1 is a side elevation of bridge spans with the warning alarms in place, the same being shown in full lines in their inactivated positions and in dotted lines in their activated positions;

FIGURE 2 is an enlarged reproduction of the central portion of **FIGURE 1**; and

FIGURE 3 is a view partly in section of one of the elements.

Two abutting bridge spans **10** and **11** are illustrated in **FIG. 1**. The span **10** is shown as having a pier **12** and the span **11** as having a pier **13**. These structures may be of appropriate material and form. They are here diagrammatically illustrated as being made of concrete and providing a road bed, constituted by the road bed section **14** on the span **10** and the corresponding section **15** on the span **11**. A continuous hand rail **16** may be provided with a post **17** to the span **10** and a post **18** to the span **11**. The hand rail may be discontinuous if desired.

The two spans **10** and **11** abut or substantially so. A gap **20** is illustrated between them in **FIGURES 1** and **2**. The size of this gap will vary in accordance with the construction factors and location of the bridge, but it normally does not exceed a given amount.

There have been accidents to traffic passing across bridges after a displacement of one of the slabs or spans with respect to the other, caused by the collision of some object in the water with a pier of the span, or other mishap. The present invention is designed to give a warning that such an event has occurred. It incorporates at least one swivelled alarm unit, although preferably there are facing units on the adjacent spans. Here two identical units **24** and **25** are shown on the respective spans **10** and **11**. The unit **24** is freely swivelled at **26** onto the span **10**, and the unit **25** is freely pivoted at **27** to the span **11**. The units **24** and **25** are designed to be swung down to an inactive, here horizontal, position until they abut stops **28** and **29**, respectively, to be releasably held there until actuated, as will appear. The stops **28** and **29** may take any suitable form such as that of bolts or pins.

FIGURE 3 shows an enlarged and more detailed view of the unit **25**. It consists of a tube **31** preferably of galvanized pipe, through which the pivot pin **27** passes. At its short end it has a counterweight **32**, this being the preferred but not only usable yieldable means to urge the unit to upright position. The tube **31** is long enough to raise the long end of the unit above the hand rail when the unit is pivoted by the counterweight to upright position illustrated in dotted lines in **FIGURE 1**. The pivoting arrangement must be free and not subject to corrosion that would prevent the swivelling action when the device is actuated. Appropriate plastic bushings or the like may be used for this purpose.

The long end of the tube **31** is adapted to receive a flare such as a red flare fusee with a thirty-minute burn period, here

illustrated at **35**. The flare is held in place by a set screw, this arrangement permitting the flare to be replaced after use, for further operation of the device. A pull cord **36** with an end loop **37** projects from the end of the flare **35**. When the cord is pulled, it will actuate the flare so that the same is ignited.

The unit **24** is identical to the unit **25** having its counterweight **40**, flare **41** and pull cord **42**.

OPERATION

10 In the inactive position into which these units are installed, the pull cord **36** is attached by having its loop **37** passed over the stop **28** on the opposite structure **10**, while the cord **42** is similarly attached to the stop **29**.

15 When either of the spans of the bridge is moved with respect to the other, the pull cords are pulled and cause the flares to ignite. In this action, the pull cords are withdrawn from the flares, freeing the units to swing to vertical positions under the action of their counterweights. This disposes the ignited flares 20 in readily visible warning positions where they will continue to appear for the duration of the period of the flare, such as for thirty minutes. This provides a warning to approaching vehicles that the roadway has been disrupted and prevents accidents.

25 While the device has been described as applied to one or more bridge spans, it is useful on other structural combinations subjected to the possibility of relative displacement, as is evident; although it has particular applicability to bridge spans because of their being subject to the impact of floating objects. As noted, the alarm may take the form of other things than a flare, and where a flare is used, it may have any desired character of light or duration of burn, or means of attachment and replacement. It is required that the alarm be normally kept inactive, and be actuated by relative displacement of the 30 structural elements upon which the device is mounted.

35 Various changes and modifications may be made within the process of this invention as will be readily apparent to those skilled in the art. Such changes and modifications are within the scope and teaching of this invention as defined by the 40 claims appended thereto.

We claim:

1. In an alarm device of the kind used to warn of relative displacement of two structures such as bridge spans that are normally disposed in an adjacent relationship to each other; the combination of a pivotable visual signal member having a swivel portion for attachment to the one structure for pivoting thereon from an inactive to an active and visible position; means normally to urge the pivotable member to the active position; means to hold the member in inactive position including a connecting element connected at one portion to the member and adapted to be attached at another portion to the other structure, whereby when the structures are displaced the connecting element will become disconnected and the pivotable member can move to its active position wherein it constitutes a visible warning, and alarm means on the pivotable member actuated to deliver an alarm when the pivotable member moves to active position.

2. In the device of Claim 1: the means to urge the pivotable member to active position comprising a counterweight arrangement the alarm means comprising a visible signal device that is displaced from a lower position to a higher position to be more visible where the pivotable member moves higher.

3. In the device of Claim 1: the connecting element being a cord, and the alarm means being a flare, the cord being connected to cause the flare to ignite when the cord is pulled, and when connected to the other structure, being adapted to be pulled when the structures are relatively displaced.

4. In the device of Claim 1: the pivotable member comprising an elongated tube having its swivel portion between its ends; the means to urge the member being a counterweight on one end of the tube; the alarm means being a flare removably and replaceably disposed in the other end of the tube, the connecting element comprising a pull cord for the flare, and hav-

ing a loop means on its free end for attachment to the opposite structure.

5. In the device of claim 4: the combination including the two relatively displaceable structures, each having a pin stop

against which its pivotable member is brought to rest when in inactive position, the pull cords of the connecting elements having loops to be engaged over the stops of the opposite structure.
